UNITED STATES PATENT OFFICE.

CLARENCE S. NATHAN, OF NEW YORK, N. Y.

DESIGN FOR A CALENDAR.

SPECIFICATION forming part of Design No. 14,028, dated July 3, 1883.

Application filed January 31, 1883. Term of patent 7 years.

To all whom it may concern:

Be it known that I, CLARENCE S. NATHAN, a citizen of the United States of America, residing at New York, in the county of New York and State of New York, have invented certain new and useful Improvements in Designs for Calendars, of which the following is a specification, reference being had therein to the accompanying drawing.

10 My invention is an improved design for calendars, which design consists, mainly, in combination with a representation of a lantern, characters, figures, or words representing dates, such as the name of the month and the number 15 of the day of the month.

In carrying out my invention I make a representation of any ordinary lantern, on which I cause to appear the name of the month and the day of the month. I prefer that the name 20 of the month shall appear in an opening in the representation of the flame of the lamp, as at *a* in the accompanying drawing, and that the numbers representing the day of the month shall appear in a corresponding opening in the 25 wick-tube or burner, as shown at *b*. On a projection from the upper rim of the lamp is shown a hole or eyelet, *c*. In addition to the characters representing the name of the month and the day thereof, other characters may be added 30 to show the day of the week, which may appear on the cover of the lantern. In the background are shown railroad-tracks and telegraph-lines, and on the former are representations of a locomotive, cars, &c., as at *d*. At *e*

is shown part of a car belonging to another 35 train, on the platform of which stands a man swinging a lantern.

It is evident that this design can be varied considerably without departing from the spirit of my invention.

40 What I claim as new is—

1. A design for calendars, consisting of a representation of a lantern provided with openings having therein characters representing dates, substantially as described.

45 2. A design for calendars, consisting of a picture of a lantern, having shown on the representation of the flame an opening through which appears the name of the month, and a representation of an opening on the burner or 50 wick-tube, through which appears the number of the day of the month, substantially as shown and described.

3. A design for calendars, herein shown and described, showing in the foreground a figure 55 of a lantern having within the representations of openings in the flame and burner the name of the month and the number of the day of the month, respectively, and in the background the locomotive and cars *d* and the car *e*, all 60 substantially as described.

In testimony whereof I affix my signature in presence of two witnesses.

CLARENCE S. NATHAN.
